UNITED STATES PATENT OFFICE.

EUGENE B. SPENZER, OF CLEVELAND, OHIO.

ELECTRICALLY-CONTROLLED RAILWAY SWITCH.

Application filed August 18, 1923. Serial No. 658,045.

To all whom it may concern:

Be it known that I, EUGENE B. SPENZER, a citizen of the United States, and a resident of Cleveland, county of Cuyahoga, and State of Ohio, have invented a new and useful Improvement in Electrically-Controlled Railway Switches, of which the following is a specification, the principle of the invention being herein explained and the best mode in which I have contemplated applying that principle, so as to distinguish it from other inventions.

This invention relates to electrically controlled railway switches. More particularly it comprises a solenoid and its associated means for turning the track switch of an electric railway, this solenoid being operated in the usual manner by the switching of the current on or off as the car goes over a contactor or breaker adjacent the location of said switch.

Switch-shifting mechanism heretofore in use has been unsatisfactory because of want of powerful action and inadequate locking or holding means.

The object of the invention is to simplify such mechanism and increase the power of the same by causing true toggle joint action and at the same time to make the latching or holding means more effective. To the accomplishment of the foregoing and related ends, said invention, then, consists of the means hereinafter fully described and pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a plan view of the switch-shifting mechanism; Fig. 2 is a side elevation thereof; and Fig. 3 is a transverse sectional view taken along the line 3—3 shown in Fig. 1, looking in the direction of the arrows.

As is clearly shown in the drawings, the solenoid 1, having windings in opposite directions upon each longitudinal half-section and a plunger or armature bar 2, is suitably disposed within a casing 3. Said casing is provided on one wall with a pair of apertured lugs 4 constituting a support for a pivoted lever arm 5. A two-part extensible rod 6 is connected by means of a

pivot pin 7 with the free end of said lever arm and is pivotally supported by means of a pin 8 adapted to be seated in a notch 9 formed in a projecting rib 10 provided on the opposite side of said casing adjacent the path of motion of the plunger or armature bar. Said mechanism thus constitutes in effect a toggle lever.

The pivoted arm 5, as is clearly shown in Fig. 3, is provided on its under side with an extension 13 which may be formed integrally therewith. Said extension lies in a vertical plane adjacent its point of junction with the pivoted arm and then extends horizontally in parallel alignment with said pivoted member 5 and at its lower end is connected by means of a link 14 with the end of the armature or plunger 2. At an intermediate point of the pivoted arm 5, slightly outward from the point at which it is joined by the extension 13 heretofore referred to, a switch guide rod 15 is connected by means of a pivot pin 16.

A vertical guide rib 17 may be formed on the bottom of the casing to serve as a support for the extension 13 and its associated parts.

The mechanism just described is intended to be operated by switch-controlling mechanism of standard type such as is disclosed in the patents to Cheatham, Nos. 696,313, March 25, 1902, and 787,827, April 18, 1905, which mechanism constitutes no part of the invention. Through such mechanism and proper control of the current on the electric car one of the windings of the solenoid is energized and the plunger is moved in a predetermined direction. As the free end of the pivoted arm approaches dead center, it will cause the compression of the coil spring and as the motion of said plunger carries said free end past dead center said coil spring will expand and cause a rapid movement of the plunger and its associated parts to its extreme limit of motion, such action thus producing a snap action and holding the switch when thus shifted to its new position of adjustment. The reverse of this operation takes place when the other winding of the solenoid is energized. Because of the toggle action of the mechanism a spring of relatively great power and positive action may be used. The plunger or armature is connected at the extreme end of the lever extension and a large mechanical advantage is thus se-

cured, as well as a compact arrangement of the mechanism.

Other modes of applying the principle of my invention may be employed instead of the one explained, change being made as regards the mechanism herein disclosed, provided the means stated by any of the following claims or the equivalent of such stated means be employed.

10 I therefore particularly point out and distinctly claim as my invention:

1. In an apparatus of the character described, a casing, a toggle mechanism mounted transversely of said casing, means associated with said toggle mechanism for holding the same in either of two positions of adjustment, an operating lever associated with an intermediate part of one of said toggle levers for pivotally actuating said

toggle mechanism, and a switch-shifting link connected to said toggle mechanism.

2. In an apparatus of the character described, a casing, a lever arm pivoted to said casing, a link connecting said lever to a shiftable switch point, a two-part extensible rod connected to the end of said lever arm and pivotally supported upon the side of said casing opposite to the point of support of said lever arm, and constituting with said lever arm a toggle mechanism, 30 a spring surrounding the sections of said extension rod and tending to space the same apart, an extensible arm on said lever arm, and actuating means connected with said extension arm. 35

Signed by me, this 15th day of August, 1923.

EUGENE B. SPENZER.
